CLAIM

The ornamental design for pants as shown and described.

DESCRIPTION

FIG. 1 is a perspective view of pants showing my new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a right side view thereof in a seated configuration; and,

FIG. 9 is a perspective view thereof in a seated configuration and in an alternate environment.

The dot-dash broken lines depict portions of the pants and environment which form no part of the claimed design and the dashed broken lines depict stitching which forms no part of the claimed design.

1 Claim, 5 Drawing Sheets
